UNITED STATES PATENT OFFICE

162,701

DECORATIVE PLATE OR SIMILAR ARTICLE

Hazel R. Yankee and Loretta May Faulconer,
Independence, Mo.

Application February 14, 1949, Serial No. 834

Term of patent 7 years

(Cl. D44—15)

To all whom it may concern:

Be it known that we, Hazel R. Yankee and Loretta May Faulconer, both citizens of the United States, both residing at Independence, Missouri, in the county of Jackson and State of Missouri, have invented a new, original, and ornamental Design for a Decorative Plate or Similar Article, of which the following is a specification, reference being had to the accompanying drawing, forming a part thereof.

Fig. 1 is a top plan view of a decorative plate or similar article, showing our new design; and Fig. 2 is an edge elevational view thereof.

We claim:

The ornamental design for a decorative plate or similar article, as shown.

HAZEL R. YANKEE.

LORETTA MAY FAULCONER.
